United States Patent Office.

BERT R. CAMPBELL, OF LOWELL, MASSACHUSETTS, ASSIGNOR TO LOWELL MANUFACTURING COMPANY, OF SAME PLACE.

Design No. 4,083, dated May 31, 1870.

DESIGN FOR A CARPET-PATTERN.

The Schedule referred to in these Letters Patent and making part of the same.

To whom it may concern:

It is known that I, ROBERT R. CAMPBELL, of the of Lowell, county of Middlesex and State of Massachusetts, have invented and produced a new and orig-
Design for a Pattern to be inwrought into Two-Ingrain, and other Carpeting, in such colors as be desired; and I do hereby declare that the
graphic print accompanying this specification
give and convey, to any one skilled in the art of carpet-weaving, a more definite and thorough descrip-
of the nature of my invention than it is in the language otherwise to convey, and it is sufficient to enable any one skilled in the art of carpet-weaving to use my invention.

Claim.

What I claim as my invention, and desire to secure by Letters Patent, is—

The configuration of the design hereunto annexed,
when made by being inwrought into two-ply, ingrain,
or other carpeting, in the form similar to the photographic print accompanying this specification.
